Inventor:

Fred Willis Gunn

By Harry G. Thomson

Atty.

UNITED STATES PATENT OFFICE.

FRED WILLIS GUNN, OF BOSTON, MASSACHUSETTS.

HOSE-CLAMPING TOOL.

Application filed August 8, 1921. Serial No. 490,581.

To all whom it may concern:

Be it known that I, FRED WILLIS GUNN, a citizen of the United States of America, residing at Boston, in the county of Suffolk and State of Massachusetts, have invented new and useful Improvements in Hose-Clamping Tools, of which the following is a specification.

This invention relates to tools for applying metallic strips, bands or wires in clamping relation, and while having other and more general fields of usefulness is particularly adapted and designed for securing flexible hose to pipes, couplings and the like. A 10 principal object of the invention is to provide a tool of this character wherein provision is made for first drawing the metallic band or wire taut, then bending the same back preferably without requiring any bodily 15 movement of the tool, to make the coupling secure as the tool is removed, and then severing the band or wire. A further object is to provide a hose clamping tool of compact construction with few parts that are strong 20 and reliable in use. The foregoing and other objects and advantages of the invention will more fully appear from the following detailed description taken in connection with the accompanying drawings, and the distinctive features of novelty will be pointed 25 out in the appended claims.

Referring to the drawings:

Fig. 1 is a side elevation of a tool embodying the invention;

Fig. 2 is a longitudinal section thereof illustrating the operation of clamping a 35 hose;

Fig. 3 is a longitudinal section similar to Figure 2 but showing the operating parts in 40 a different position;

Fig. 4 is a plan view showing the tool applied for clamping a hose; and

Fig. 5 is a partial longitudinal section 45 illustrating the clearing of the tool of the wire extremity left therein.

10 indicates the body of the tool which may have its intermediate portion 10^a of a U-shaped cross section with front and rearward lateral cheek portions 10^b, 10^c, this 50 body constituting a housing for the operating members. At the inner end of the body a pin 11 is fitted transversely therethrough for turning movement, the range whereof is limited by an arm 12 projecting from the 55 pin at one end thereof and engageable with

a stop 13 on the body. This pin has a transverse passage 14 therethrough intermediate its length of a dimension to receive the end portion of the hose clamping band B therethrough. A block 15 is located between the 60 cheek portions 10^b and mounted to turn upon the pin 11. This block has a passage 16 through its front portion adapted in one position of the block to receive the hose clamping band or wire. This block is 65 equipped with a pin 17 adjacent the top thereof which is engaged by a draw-bar 18 extending outwardly through the body of the tool and engaged at its other end with a pin 19 borne at the outer end of a short 70 arm 20. The arm 20 which is located between the cheek portions 10^c is mounted to turn with a stout pin 21 which is pivoted at the outer end of the tool body and equipped at an outer projecting end thereof with a 75 squared head 22. A pin 23 is fitted for turning movement transversely in the body a small distance outward from the pin 11 and has at one end a squared projecting head 24. This pin has a transverse passage 25 there- 80 through adapted to register with the passages 14, 16 when the parts are turned to the positions shown in Figure 2, and to then receive the extremity B' of the clamping band therethrough. A cutter member 26 is piv- 85 oted in the body at 27 in position so that when it is swung upward as indicated in Figure 5 it engages the periphery of the pin 23 in an approximate tangential relation for the purpose of clearing out the wire extremity as 90 presently further explained. The front projecting portion of the block 15 comprises a circular portion 15^a extending to a point just in advance of the passage 16 where it is cut away as indicated at 15^b in a flat, beveled 95 face, the purpose of which is to permit the clamping band to be bent back more abruptly from the clamp loop L by the operation of the tool. In use the head 15 is adjusted so that the band extremity B' may be 100 passed through the passages 16, 14, and the pin 23 is set so that said extremity may be passed through the passage 25 thereof. Then upon turning the pin 23 by the application of a wrench or like tool to its head 105 24 the clamping band or wire is drawn taut under the requisite degree of tension to clamp the hose securely, this resulting in wrapping the band or wire to a greater or less extent around the pin 23 as seen in 110

Figure 3. Then the pin 21 is turned in a clockwise direction as seen in the drawings, drawing upon the bar 18 and turning the head 15. This results in bending the band 5 extremity sharply around the loop L, i. e. from the position shown in Figure 2 to that shown in Figure 3, making enough of a bend at this point so that the clamp will be secure when the tool is removed. During 10 the first part of this movement of the block 15 the pin 11 turns with it until the arm 12 engages the stop 13 whereupon a further movement of the head 15 results in shearing off the clamping band at the inner end of 15 the passage 16 by engagement with the opposite wall of the passage 14. This leaves a cut off extremity of the wire partly wound around the pin 23 which is readily removed by moving up the cutter 26 as indicated in 20 Figure 5 and turning the pin 23 further so as to sever the band. The described means for producing a sharp bend in the clamping band after it has been drawn taut and before severance thereof, by the oscillation of 25 the head 15 is of particular value and importance in using the tool in places where operating space is limited and where it would not be possible to swing the tool bodily, being thus well adapted for making 30 connections to automobile radiators or the like. I am aware that the invention may be embodied in other specific forms without departing from the spirit or essential attributes thereof, and I therefore desire the 35 present embodiment to be considered in all respects as illustrative and not restrictive, reference being had to the appended claims rather than to the foregoing description to indicate the scope of the invention.

Having described my invention, what I claim as new and desire to secure by Letters Patent is:

1. A hose clamping tool comprising a body equipped with a head at one end thereof 45 with a passage therethrough to receive a clamping band or wire, means for drawing the clamping band taut, and means for oscillating said head in the body to bend the clamping band for the purpose stated.

2. A hose clamping tool comprising a body, a pivot pin at one end of the body, a head mounted upon the pivot pin, said head and pin having passages therethrough to receive a clamping band or wire, means for 55 oscillating said head, means restraining the oscillation of said pin after a predetermined movement thereof, whereby to sever the clamping band, and means for preliminarily drawing the clamping band taut through 60 said passages.

3. A hose clamping tool comprising a body, a pivot pin at one end of the body, a head mounted upon the pivot pin, said pin and said head having passages therethrough 65 to receive a clamping band, and said pin

mounted for limited turning movement, means for oscillating said head to first bend the band and then by co-operation with said pin to sever the same, said means having a connection operable at the end of the body 70 opposite said head, and means for preliminarily drawing the band taut through said passages of said pin and head.

4. A hose clamping tool comprising an elongated body, a pin mounted for limited 75 turning movement at one end thereof, a head mounted to turn upon said pin, said head and said pin having passages therethrough, registering in one position to receive a clamping band or wire therethrough, 80 a second pin mounted in the body equipped to engage the extremity of the clamping band to draw the same taut, and means for oscillating said head to first bend the clamping band and then to sever the same by co- 85 operation with said pin.

5. A hose clamping tool comprising a body, a bending means for a clamping band or wire and provided with means for cutting said band or wire, means for drawing the 90 clamping band or wire taut, a pivotal mounting for the bending and cutting means co-operating with the cutting means of the bending means for shearing the wire, and means for severing the band or wire from 95 the drawing means.

6. A hose clamping tool, comprising a body, a bending means for a clamping band or wire, means for drawing said clamping band or wire taut, and means cooperating 100 with the bending means for cutting the clamping band or wire, co-operating cutting means having a simultaneous rotary movement during a portion of the rotary movement of the bending means, and means for 105 causing simultaneous rotation of the co-operating cutting means and the bending means, said means adapted to continue rotation of the bending means after the co-operating cutting means has been checked in its rotary 110 movement.

7. A hose clamping tool, comprising a body, a bending means for a clamping band or wire, means for holding the clamping band or wire, means for rotating the bending means on the holding means, and means on the bending means co-operating with the holding means for shearing the wire when the bending means is rotated relative to the holding means.

8. A hose clamping tool, comprising a body, a bending means for clamping band or wire rotatable on the body, means co-operating with the bending means for cutting the clamping band, said last mentioned means comprising a pivotal mounting for the bending means, means for rotating the bending means, said pivotal means being rotatable with the bending means, and means for limiting the rotary movement of the pivotal 125 means.

means while the bending means continues its rotary movement.

9. A hose clamping tool, comprising a body, a bending means for a clamping band or wire rotatable on the body, means cooperating with the bending means for cutting the clamping band, said last mentioned means comprising a pivotal mounting for the bending means, means for rotating the bending means, said pivotal means being rotatable with the bending means, means for limiting the rotary movement of the pivotal means while the bending means continues its rotary movement, and means for drawing the clamping band or wire taut.

10. A hose clamping tool, comprising an elongated body, a pin mounted for limited turning movement at one end thereof, a head mounted to turn upon said pin, said head and pin being provided with passages there-through registering in one position to receive a clamping band or wire, a second pin

mounted in the body and provided with a passage adapted to receive the end of the clamping band and rotatable for drawing 25 the clamping band taut, an arm connected with the first mentioned pin and rotatable therewith, a lug on the body projecting into the path of the oscillating arm for limiting the movement of the arm and pin, and means 30 for oscillating the head to first bend the clamping band and rotate both the head and the first mentioned pin, said oscillating arm adapted to engage the lug in its path for preventing rotation of the pin whereby a 35 continued rotation of the head causes severing of the clamping band.

In testimony whereof I affix my signature in presence of two witnesses.

FRED WILLIS GUNN.
